United States Patent Office

Des. 186,789
Patented Dec. 1, 1959

186,789

COIN BOX

George C. Estrem, Slayton, Minn., assignor to Estrem Distributing, Inc., St. Paul, Minn., a corporation of Minnesota

Application June 29, 1959, Serial No. 56,577

Term of patent 14 years

(Cl. D52—4)

FIG. 1

FIG. 2

FIG. 3

I claim:

The ornamental design for a coin box, as shown.
